(57) **ABSTRACT**

It has been difficult to suppress electromagnetic wave that propagates within a suspended substrate. The structure according to the present invention is provided with: a first conductor plane and a second conductor plane that are disposed parallel to each other; a dielectric plane that is disposed between the first and second conductor planes via a hollow region so as to be parallel to the first and second conductor planes; a first transmission line disposed on a surface that is of the dielectric plane and that opposes the first conductor plane; and a second transmission line disposed on a surface that is of the dielectric plane and that opposes the second conductor plane, wherein the first transmission line and the second transmission line are electrically connected to each other.

APPLICATIONS**

This application is a National Stage of International Application No. PCT/JP2017/012379, filed Mar. 27, 2017, claiming priority based on Japanese Patent Application No. 2016-070663, filed Mar. 31, 2016, the contents of all of which are incorporated herein by reference in their entirety.

TECHNICAL FIELD

The present invention relates to a structure body, layered structure of a structure body, and an antenna structure.

BACKGROUND ART

In a device using a high frequency electromagnetic wave such as an antenna device or a wireless communication device, a structure body including a transmission line a part of which is hollow is used in order to suppress a loss at the transmission line. An art related to such a structure body is disclosed in Patent Literature 1 (PTL1).

PTL1 discloses an art related to a suspended substrate. A suspended substrate is provided with parallel flat plates including two conductor planes that are substantially parallel to each other and a dielectric substrate disposed between the parallel flat plates in a floating manner. The dielectric substrate is provided with a signal line that forms a transmission line. Having a hollow part as a part of the gap between the parallel flat plates reduces dielectric material, thereby suppressing dielectric loss. As a result, a high frequency signal is transmitted efficiently.

SUMMARY OF INVENTION

Technical Problem

A problem in the related art is the difficulty in suppressing an electromagnetic wave that propagates inside the suspended substrate.

Generally, at a point with discontinuous characteristic impedance or in a situation that high-mode is generated, there is a possibility that a part of the high frequency signal that propagates in the transmission line does not propagate along the signal line and is emitted as an electromagnetic wave, and leaks to the inside of the parallel flat plates. When the electromagnetic wave leaks to the inside of the parallel flat plates (hereinafter the electromagnetic wave that leaks is referred to as leaked electromagnetic wave), the leaked electromagnetic wave has a possibility to cause coupling to other devices or to emit to the outside. Thus, sometimes leakage countermeasure such as short-circuiting the parallel flat plates is performed. However, since a suspended substrate has a hollow region in a part of the substrate, it is difficult to short-circuit the parallel flat plates.

An objective of the present invention is to provide a structure body that suppresses the leaked electromagnetic

2

wave that propagates inside the suspended substrate, a layered structure of the structure body, and an antenna structure.

Solution to Problem

A structure body in the present invention comprises:

a first conductor plane and a second conductor plane disposed in parallel;

10 a dielectric plane that is disposed in parallel to the first conductor plane and the second conductor plane between the first conductor plane and the second conductor plane via a hollow region;

15 a first transmission line that is disposed on a surface facing the first conductor plane of the dielectric plane, at least one of whose ends is an open end; and

20 a second transmission line that is disposed on a surface facing the second conductor plane of the dielectric plane, at least one of whose ends is an open end;

25 wherein the first transmission line and the second transmission line are electrically connected to each other.

A layered structure in the present invention comprises:

a first conductor plane and a second conductor plane disposed in parallel;

30 a third conductor plane that is disposed in parallel to the first conductor plane and the second conductor plane, and in parallel to the surface of the second conductor plane opposite to the surface facing the first conductor plane;

35 a first dielectric plane that is disposed in parallel to the first conductor plane and the second conductor plane between the first conductor plane and the second conductor plane via a hollow region;

a second dielectric plane that is disposed in parallel to the second conductor plane and the third conductor plane between the second conductor plane and the third conductor plane via another hollow region;

40 a first transmission line that is disposed on a surface of the first dielectric plane facing the first conductor plane, and on a surface of the second dielectric plane facing the surface of the second conductor plane, and at least one end of which is an open end;

45 a second transmission line that is disposed on a surface of the first dielectric plane facing the second conductor plane and on a surface of the second dielectric plane facing the third conductor plane, and at least one end of which is an open end;

50 a first suspended transmission line that is disposed on the first dielectric plane, and one end of which is an open end; and

55 a second suspended transmission line that is disposed on the second dielectric plane, and one of which is an open end;

wherein the second conductor plane includes an opening at a position opposing to an open end of the first suspended transmission line and an open end of the second suspended transmission line;

60 wherein the first transmission line and the second transmission line are electrically connected to each other; and

65 a plurality of unit structures are disposed to surround open ends of the first suspended transmission line and the second suspended transmission line, where the unit structure is configured by the first transmission line and the second transmission line.

An antenna structure in the present invention comprises:

a first conductor plane and a second conductor plane disposed in parallel;

a dielectric plane that is disposed in parallel to the first conductor plane and the second conductor plane between the first conductor plane and the second conductor plane via a hollow region;

a first transmission line that is disposed on a surface facing the first conductor plane of the dielectric plane, at least one end of which is an open end; and

a second transmission line that is disposed on a surface of the dielectric plane facing the second conductor plane, at least one end of which is an open end; and

a suspended transmission line that is disposed on the dielectric plane, and one of which is an open end;

wherein the first conductor plane includes an opening at a position opposing to an open end of the suspended transmission line;

the first transmission line and the second transmission line are electrically connected to each other; and

a plurality of unit structures are disposed to surround an open end of the suspended transmission line, wherein the unit structure is configured by the first transmission line and the second transmission line.

Advantageous Effect of Invention

The effect of the present invention is that the structure body, the layered structure thereof and the antenna structure suppress the leaked electromagnetic wave that propagates inside the suspended substrate.

BRIEF DESCRIPTION OF DRAWINGS

FIGS. 1A to 1C are cross-sectional views illustrating a configuration of a structure body 100 of the first example embodiment of the present disclosure.

FIGS. 2A and 2B are top views illustrating a configuration of the structure body 100 of the first example embodiment of the present disclosure.

FIGS. 3A and 3B are diagrams illustrating an operation of the structure body of the first example embodiment of the present disclosure.

FIG. 4 is a diagram illustrating scattering parameters of the structure body 100 of the first example embodiment of the present disclosure.

FIG. 5 is a diagram illustrating a configuration of a structure body 200 of the second example embodiment of the present disclosure.

FIG. 6 is a diagram illustrating a configuration of a structure body 300 of the third example embodiment of the present disclosure.

FIGS. 7A to 7D are diagrams illustrating a configuration of a variation of a first transmission line 304 and a second transmission line 305 of the third example embodiment of the present disclosure.

FIG. 8 is a diagram illustrating a configuration of a structure body 400 of the fourth example embodiment of the present disclosure.

FIG. 9 is a diagram illustrating a configuration of a structure body 500 of the fifth example embodiment of the present disclosure.

FIG. 10 is a diagram illustrating a configuration of a variation of the structure body 500 of the fifth example embodiment of the present disclosure.

FIGS. 11A to 11C are diagrams illustrating a configuration of a structure body 600 of the sixth example embodiment of the present disclosure.

FIG. 12 is a diagram illustrating a configuration of the layered structure 700 of the seventh example embodiment of the present disclosure.

FIG. 13 is a diagram illustrating a configuration of the antenna structure 800 of the eighth example embodiment of the present disclosure.

FIG. 14 is a diagram illustrating a configuration of the structure body 900 of the ninth example embodiment of the present disclosure.

EXAMPLE EMBODIMENT

Hereinafter, with reference to the drawings, the example embodiments of the present invention are described in detail. Note that, in each drawing and each example embodiment in the description, same reference numerals are used to such the component provided with similar function.

First Example Embodiment

FIG. 1 and FIG. 2 are diagrams illustrating a configuration of the structure body 100 of the first example embodiment of the present disclosure. FIGS. 1A and 1B are cross-sectional views in A-A' of the structure body 100 illustrated in FIGS. 2A and 2B, respectively. FIG. 2 is a top view of the structure body 100 as viewed from a first conductor plane 101 side out of the directions perpendicular to the first conductor plane 101 (hereinafter, the top is defined similarly herein).

The structure body 100 is configured by provided with a parallel flat plate configured by provided with a first conductor plane 101 and a second conductor plane 102 that are substantially parallel to each other, a dielectric plane 103 disposed therebetween, a first transmission line 104 having the dielectric plane 103 as the support member and disposed on the surface of the first conductor plane 101 side, a second transmission line 105 that is disposed on the surface of the second conductor plane 102 side of the dielectric plane 103, and a conductor via 106 that connects the first transmission line 104 and the second transmission line 105.

The dielectric plane 103 has hollow regions 107 and 108, sandwiched with the first conductor plane 101 and sandwiching with the second conductor plane 102, respectively.

One end of each of the first transmission line 104 and the second transmission line 105 is an open end, and the other ends are coupled to each other by the conductor via 106. The first transmission line 104 and the second transmission line 105 are disposed in such a way that each open end does not overlap in the top view (refer to FIG. 2).

For example, in the structure body 100, the first transmission line 104 and the second transmission line 105 may be disposed in a V-shape as illustrated in FIG. 1A and FIG. 2A, or may be disposed in an I-shape as illustrated in FIG. 1B and FIG. 2B.

The structure body 100 may not necessarily use the conductor via 106 in the case the first transmission line 104 and the second transmission line 105 can be connected to each other, as illustrated in FIG. 1C. As illustrated in FIG. 1C, in the structure body 100, the first transmission line 104 and the second transmission line 105 may be disposed in different layers without using the conductor via 106, and an end that is not the open end of each of the first transmission line 104 and the second transmission line 105 may contact each other and be electrically connected.

FIG. 3 is a diagram describing an operation of the structure body 100 illustrated in FIG. 1A. FIG. 3A is a cross-sectional view in A-A' of the structure body 100, and

FIG. 39 is a top view of the structure body 100. The operations of the structure body 100 in FIGS. 1B and 1C can be described in the similar principle as FIG. 3.

With the structure body 100 of the example embodiment, when the impedance Z between the parallel flat plates configured by provided with the first conductor plane 101 and the second conductor plane 102 is substantially zero or inductive, the propagation constant is an imaginary number, and therefore the propagation of the electromagnetic wave can be suppressed. Especially, the suppressing effect is high when the impedance Z is substantially zero.

In the structure body 100, in the case the leaked electromagnetic wave 113 propagates between the parallel flat plates configured by provided with the first conductor plane 101 and the second conductor plane 102 (i.e. in the case of propagation through a unit structure including the first transmission line 104, the second transmission line 105 and the conductor via 106), electric field distribution is induced between the first transmission line 104 and the first conductor plane 101, and between the second transmission line 105 and the second conductor plane 102, and the first transmission line 104 and the second transmission line 105 operate as stubs.

It is assumed that the input impedance between the transmission line 104 and the conductor plane 101 when viewed from the conductor via 106 side to the open end side of the first transmission line 104 is Z_{in1} , and the input impedance between the transmission line 105 and the conductor plane 102 when viewed from the conductor via 106 side to the open end side of the second transmission line 105 is Z_{in2} . Here, the impedance Z between the parallel flat plates configured by provided with the first conductor plane 101 and the second conductor plane 102 is expressed substantially by the sum of Z_{in1} , the inductance of the conductor via 106 and Z_{in2} .

In order to suppress the leaked electromagnetic wave 113, the first transmission line 104 and the second transmission line 105 are preferably designed to satisfy the following relationship: for example, the length L from the connection to the conductor via 106 to each open end is substantially $L=(2n+1)\times\lambda/4$, where λ is the wavelength at the operating frequency. Here, the parameter n is an integer equal to or larger than 0, and $n=0, 1, 2, 3, \dots, n$.

With the structure body 100 taking the above configuration, in the first transmission line 104 and the first conductor plane 101, the input impedance Z_{in1} between the transmission line 104 and the conductor plane 101 when seeing the open end side of the first transmission line 104 from the conductor via 106 side becomes substantially zero. This means that the first transmission line 104 and the first conductor plane 101 are short-circuited.

Similarly, in the second transmission line 105 and the second conductor plane 102, the input impedance Z_{in2} between the transmission line 105 and the conductor plane 102 when seeing the open end side of the second transmission line 105 from the conductor via 106 side becomes substantially zero. This means that the second transmission line 105 and the second conductor plane 102 are short-circuited.

The above effect and the inductance of the conductor via 106, the structure body 100 can make the impedance Z between the first conductor plane 101 and the second conductor plane 102 inductive, as illustrated in the right side of FIGS. 3A and 3B. As a result, the structure body 100 can suppress the propagation of the leaked electromagnetic wave 113. Especially, when the inductance of the conductor via 106 is sufficiently small, the impedance Z between the first

conductor plane 101 and the second conductor plane 102 can be regarded as substantially zero. In this case, the structure body 100 can further suppress the propagation of the leaked electromagnetic wave 113.

5 In the structure body 100 of the first example embodiment, the coupling between the first transmission line 104 and the second transmission line 105 can be suppressed by disposing the first transmission line 104 and the second transmission line 105 in such a way as to the open ends thereof do not overlap in a top surface view.

In the example embodiment, the first transmission line 104 and the second transmission line 105 may be any length as long as the impedance Z between the parallel flat plates configured by provided with the first conductor plane 101 and the second conductor plane 102 is substantially zero or inductive.

Scattering parameters related to the structure body 100 of the example embodiment are illustrated in FIG. 4. It is 20 assumed that, in the structure body 100 illustrated in FIG. 1A, when assuming the left edge as analysis port 1 and right edge as analysis port 2, the scattering parameter representing the magnitude of the power reflection of the Transverse Electromagnetic (TEM) wave to the analysis port 1 is S11, and the scattering parameter representing the magnitude of the power transmittance from the analysis port 1 to the analysis port 2 is S21. According to FIG. 4, at a predetermined frequency f_0 , S11 shows a high peak and S21 shows a low peak. The meaning is that the propagation of the TEM wave is suppressed by the unit structure including the first conductor plane 101, the first transmission line 104 and the conductor via 106, and the unit structure including the second conductor plane 102, the second transmission line 105 and the conductor via 106.

With reference to FIG. 4, the structure body 100 of the example embodiment is effective for suppressing the propagation of the leaked electromagnetic wave in the parallel flat plates.

40 Note that the connection of the first transmission line 104 and the second transmission line 105 may not necessarily be the ends of the first transmission line 104 and the second transmission line 105, but may be any points except for the open ends.

45 The thicknesses h_1 and h_2 of the hollow regions 107 and 108 of the first example embodiment respectively may be equal or unequal to each other.

Second Example Embodiment

The structure body 200 of the second example embodiment of the present disclosure is described with reference to FIG. 5.

The structure body 200 in FIG. 5 is different from the 55 structure body 100 of the first example embodiment in that the first transmission line 104 and the second transmission line 105 are disposed in an overlapping manner when viewed from the top (from the first conductor plane side out of the directions perpendicular to the first conductor plane), and t is greatly different from h_1 and h_2 when h_1 and h_2 are the thicknesses of the hollow regions 107 and 108 respectively, and t is the thickness of a dielectric plane 203. In the structure body 200, since t is set to be larger than h_1 and h_2 , even when the open ends of the first transmission line 104 and the second transmission line 105 are disposed to overlap when viewed from the top, the coupling between the stubs are suppressed, and therefore, in a similar manner to the first

example embodiment, the propagation of the leaked electromagnetic wave in the parallel flat plates can be suppressed.

Third Example Embodiment

The structure body 300 of the third example embodiment of the present disclosure is described with reference to FIG. 6.

The structure body 300 of the third example embodiment is different from the structure body 100 of the first example embodiment in that the shape of the first transmission line 104 and the second transmission line 105 of the first example embodiment are not linear shape but folding back shape. Regarding to the structure body 300 of the third example embodiment, by flexibly mounting the shape of the first transmission line 304 and the second transmission line 305, the size of the structure body 300 can be decreased.

With the structure body 300 of the example embodiment, in a similar manner to the first example embodiment, the propagation of the leaked electromagnetic wave in the parallel flat plates can be suppressed.

In the example embodiment, the first transmission line 304 and the second transmission line 305 are U-shaped folding back shape however, other shape may be adopted. For example, L-shape, curved shape, spiral shape, meandering shape or the like as illustrated in FIGS. 7A to 7D may be adopted.

Fourth Example Embodiment

The structure body 400 of the fourth example embodiment of the present disclosure is described with reference to FIG. 8.

In the structure body 400 of the fourth example embodiment, each of the first transmission line 404 and the second transmission line 405 has a plurality of branch wires. In the example embodiment, the number of branch wires is assumed to be two however, the number may be equal to or more than three. The two branch wires that are included by each of the first transmission line 404 and the second transmission line 405 respectively have different lengths L_1 and L_2 , from the connection portion to the conductor via 106 to each open end. The branch wires whose lengths are different operate in different frequencies respectively, and the branch wires are adjusted to satisfy the following conditions.

The L_1 is designed to satisfy $L_1 = (2s+1) \times \lambda_1 / 4$ for the λ_1 that is the wavelength at the operating frequency. Here, the parameter s is an integer equal to or larger than 0 and $s=0, 1, 2, \dots, s$.

Similarly, the L_2 is designed to satisfy $L_2 = (2t+1) \times \lambda_2 / 4$, for the λ_2 that is the wavelength at the operating frequency. Here, the parameter t is an integer equal to or larger than 0, and $t=0, 1, 2, \dots, t$.

With the configuration described above, since the first transmission line 404 and the second transmission line 405 perform resonance operation at a plurality of frequencies originating from the length of each of the plurality of branch wires, the structure body 400 operates at a plurality of frequencies.

Fifth Example Embodiment

The structure body 500 of the fifth example embodiment of the present disclosure is described with reference to FIG. 9 and FIG. 10.

The structure body 500 of the fifth example embodiment is different from the first example embodiment in that a suspended strip line 512 configured by provided with a third transmission line 509 and a fourth transmission line 510 and a plurality of conductor vias 511 on the dielectric plane 103 in addition to the configuration of the structure body 100 of the first example embodiment is disposed. On the structure body 500, a plurality of unit structure including a first transmission line 104, a second transmission line 105, and a conductor via 106 surrounding the suspended strip line 512 formed on the suspended substrate may be disposed. For example, the unit structure may be disposed periodically.

In the suspended strip line 512, the fourth transmission line 510 and a plurality of conductor vias 511 may not necessarily be used, and only the third transmission line 509, as illustrated in FIG. 10, may be included.

Sixth Example Embodiment

The structure body 600 of the sixth example embodiment of the present disclosure is described with reference to FIG. 11.

The structure body 600 of FIG. 11A is configured by provided with parallel flat plates configured by provided with the first conductor plane 101 and the second conductor plane 102 that are substantially parallel to each other, a dielectric plane 103 disposed therebetween, and a transmission line 609 whose length is L disposed on the dielectric plane 103.

Resonator operates when the length L of the transmission line 609 roughly satisfying relationship as $L = n \times \lambda / 2$, where λ is the wavelength at the operation frequency and n is an integer equal to or larger than 1, and the leaked electromagnetic wave that propagates in the parallel flat plates can be suppressed. Note that the thicknesses h_1 and h_2 of the hollow regions 107 and 108 may be equal or unequal to each other.

FIG. 11B illustrates a configuration that the transmission line 609 of FIG. 11A is replaced with the first transmission line 604, conductor via 606 and the second transmission line 605. An end of each of the first transmission line 604 and the second transmission line 605 that is not an open end is coupled to each other by conductor via 606. Similar to the length L of the transmission line 609 of the FIG. 11A, the total length L of the first transmission line 604, conductor via 606 and the second transmission line 605 preferably satisfies $L = n \times \lambda / 2$ to the wavelength λ at the operation frequency where n is an integer equal to or larger than 1, when the propagation of the leaked electromagnetic wave in the parallel flat plates is suppressed. Note that the thicknesses h_1 and h_2 of the hollow regions 107 and 108 may be equal or unequal to each other.

In FIG. 11B, the first transmission line 604 and the second transmission line 605 have different lengths from the coupling to the conductor via 606 to each open end. However, as a matter of course, the lengths of the first transmission line 604 and the second transmission line 605 from the coupling to the conductor via 606 to each open end may be equal.

FIG. 11C illustrates a configuration that the transmission line 609 of FIG. 11A is replaced with the first transmission line 604 and the second transmission line 605. An end of each of the first transmission line 604 and the second transmission line 605 are disposed on different layers, and connected to each other at ends that are not the open ends. Here, similar to the length L of the transmission line 609 of the FIG. 11A, the total length L of the first transmission line 604 and the second transmission line 605 preferably satisfies $L = n \times \lambda / 2$ to the wavelength λ where n is an integer equal to

or larger than 1, when the propagation of the high frequency signal in the parallel flat plates is suppressed. Note that the thicknesses h_1 and h_2 of the hollow regions **107** and **108** may be equal or unequal to each other.

In FIG. 11C, the first transmission line **604** and the second transmission line **605** have different lengths from the connection of the first transmission line **604** and the second transmission line **605** to each open end. However, as a matter of course, the lengths of the first transmission line **604** and the second transmission line **605** from the connection of the first transmission line **604** and the second transmission line **605** to each open end may be equal.

In the example embodiment, the first transmission line **604** and the second transmission line **605** have a linear shape; however, other shape may be adopted. For example, similar to the first transmission line **304** and the second transmission line **305** of the third example embodiment, various folding back shapes may be adopted.

Seventh Example Embodiment

The layered structure **700** of the seventh example embodiment of the present disclosure is described with reference to FIG. 12.

The layered structure **700** of the seventh example embodiment is the configuration when the structure body **500** of the fifth example embodiment is layered.

The layered structure **700** illustrated in FIG. 12 includes parallel flat plates formed by three planes that are a first conductor plane **701**, a second conductor plane **702** and a third conductor plane **703**, a first dielectric plane **704** and a second dielectric plane **705**, a first suspended strip line **711** and a second suspended strip line **712** that are disposed on the first dielectric plane **704** and the second dielectric plane **705** respectively and one end of each is an open end, and a plurality of unit structures **720** disposed around each open end of the first suspended strip line **711** and the second suspended strip line **712**.

The unit structure **720** is configured by the first transmission line **104**, the second transmission line **105** and the conductor via **106** of the first example embodiment. Note that the conductor via **106** may not necessarily be included. By replacing the dielectric plane **103** of the first example embodiment with the first dielectric plane **704** and the second dielectric plane **705** of the example embodiment, the unit structure **720** can be configured as the first dielectric plane **704** and the second dielectric plane **705**.

The unit structure **720** may be disposed periodically in the example embodiment.

The high frequency signal that propagates within the suspended strip line is transmitted from the first suspended strip line **711** to the second suspended strip line **712** via the slot **713** disposed on the second conductor plane **702**, as illustrated by the arrows in FIG. 12. The high frequency signal may be transmitted from the second suspended strip line **712** to the first suspended strip line **711** via the slot **713** disposed on the second conductor plane **702**, in the opposite direction of the arrows.

In the layered structure **700**, when the plurality of unit structures **720** are not disposed, a part of the high frequency signal transmitted from the first suspended strip line **711** intrudes to the slot **713** and transmitted to the second suspended strip line **712**, however, a part of the remaining high frequency signal has a possibility to propagate, not along the second suspended strip line **712**, but to the inside of the two parallel flat plates formed by the first conductor plane **701**, the second conductor plane **702** and the third

conductor plane **703** as a leaked electromagnetic wave. This is because the characteristic impedance at the slot **713** and the open end of the suspended strip line is discontiguous with regard to the suspended strip line **711** and **712**. In order to prevent the propagation of the leaked electromagnetic wave, a plurality of unit structures **720** are disposed in FIG. 12. As a result, the signal transmission between the suspended strip lines in the layered structure **700** can be performed efficiently.

Eighth Example Embodiment

The antenna structure **800** of the eighth example embodiment of the present disclosure is described with reference to FIG. 13.

The antenna structure **800** illustrated in FIG. 13 includes parallel flat plates configured by the first conductor plane **101** and the second conductor plane **102**, and a dielectric plane **103** disposed between the first conductor plane **101** and the second conductor plane **102**, each sandwiching the hollow regions **107** and **108**. The dielectric plane **103** has a suspended strip line **805** one of whose ends is an open end and a plurality of unit structures **720**, the unit structures **720** are disposed to surround the open end of the suspended strip line **805**, and the first conductor plane **101** has a slot **808** at an opposed position to the open end of the suspended strip line **805** viewed from the direction perpendicular to the first conductor plane **101**.

The slot **808** operates as an antenna element that receives the electromagnetic wave from outside and transmits to the suspended strip line **805**, or in an opposite manner, emits the high frequency signal transmitted from the suspended strip line **805** to the outside.

The plurality of unit structures **720** are disposed to prevent the propagation of the leaked electromagnetic wave from the suspended strip line **805** to the inside of the parallel flat plates formed by the first conductor plane **101** and the second conductor plane **102**, similar to the seventh example embodiment.

Ninth Example Embodiment

The structure body **900** of the ninth example embodiment of the present disclosure is described with reference to FIG. 14.

The structure body **900** of FIG. 14 has a first conductor plane **101** and a second conductor plane **102** that are substantially parallel to each other, a conductor plane **103** disposed therebetween, a first and a second transmission lines disposed on the conductor plane **103**, a conductor via, and hollow regions **107** and **108**. In addition, a spacer **907** is disposed to the hollow regions **107** and **108** as a supporting member between the conductor plane and the dielectric plane in order to secure a constant thickness.

The material used for the spacer **907** may be any of conductor, dielectric, or magnetic substance as long as the mechanical strength is secured.

The spacer **907** is preferably disposed at a position far from the unit structure **720** in such a way as not to affect the operation thereof. The spacer **907** may not necessarily be electrically connected to the first conductor plane **101**, the second conductor plane **102** and the dielectric plane **103**.

The present invention has been described above with each example embodiment and the variation, however, the present invention is not limited to the above example embodiments. Within the scope of the present invention, the configuration and the detail of the present invention may be

11

applied with various changes and combinations that may be understood by a person skilled in the art.

Each of the example embodiments described above may be described as the supplementary note below and is not limited.

(Supplementary Note 1)

A structure body including:

a first conductor plane and a second conductor plane disposed in parallel;

a dielectric plane that is disposed in parallel to the first conductor plane and the second conductor plane between the first conductor plane and the second conductor plane via a hollow region;

a first transmission line that is disposed on a surface facing the first conductor plane of the dielectric plane; and

a second transmission line that is disposed on a surface facing the second conductor plane of the dielectric plane;

in which the first transmission line and the second transmission line are electrically connected to each other.

(Supplementary Note 2)

The structure body according to claim 1, in which the first transmission line and the second transmission line are provided with a plurality of branch wires whose lengths are different, respectively.

(Supplementary Note 3)

The structure body according to supplementary note 2, in which lengths L_m from the connection of the first transmission line and the second transmission line to the end of the plurality of branch wires satisfy $L_m = (2n+1) \times \lambda_m / 4$, where λ_m is a wavelength at an operating frequency and n is an integer equal to or larger than 0.

(Supplementary Note 4)

The structure body according to supplementary note 1, further including at least one suspended transmission line disposed on the dielectric plane,

in which the first transmission line and the second transmission line are disposed around the suspended transmission line.

(Supplementary Note 5)

The structure body according to the supplementary note 4, including a plurality of unit structures configured by the first transmission line and the second transmission line,

in which the plurality of unit structures are disposed to surround the suspended transmission line.

The invention claimed is:

1. A structure body comprising:

a first conductor plane and a second conductor plane disposed in parallel;

a dielectric plane that is disposed in parallel to the first conductor plane and the second conductor plane, and between the first conductor plane and the second conductor plane via a hollow region;

a first transmission line that is disposed on a surface facing the first conductor plane of the dielectric plane, at least one of whose ends is an open end; and

a second transmission line that is disposed on a surface facing the second conductor plane of the dielectric plane, at least one of whose ends is an open end;

wherein the first transmission line and the second transmission line are electrically connected to each other, wherein the first transmission line and the second transmission line are disposed in such a way that open ends thereof overlap with each other when viewed from the direction perpendicular to the first conductor plane, and wherein a thickness of the dielectric plane is greater than a thickness of the hollow region.

2. The structure body according to claim 1, wherein the first transmission line and the second transmission line are disposed in such a way that open ends thereof do not overlap with each other when viewed from the direction perpendicular to the first conductor plane.

3. The structure body according to claim 1, wherein lengths L from the connection of the first transmission line and the second transmission line to open ends of the first transmission line and the second transmission line respectively satisfy $L = (2n+1) \times \lambda / 4$, where λ is a wavelength at an operating frequency and n is an integer equal to or larger than 0.

4. The structure body according to claim 1, wherein the first transmission line and the second transmission line are disposed in a folded manner.

5. The structure body according to claim 1, wherein each of the first transmission line and the second transmission line comprises a plurality of branch wires whose lengths are different.

6. The structure body according to claim 1, further comprising at least one spacer between the first conductor plane and the dielectric plane, and between the second conductor plane and the dielectric plane, respectively.

7. A structure body comprising:

a first conductor plane and a second conductor plane disposed in parallel;

a dielectric plane that is disposed in parallel to the first conductor plane and the second conductor plane, and between the first conductor plane and the second conductor plane via a hollow region;

a first transmission line that is disposed on a surface facing the first conductor plane of the dielectric plane, at least one of whose ends is an open end;

INDUSTRIAL APPLICABILITY

The application examples of the present invention are a communication device, antenna device or the like.

a second transmission line that is disposed on a surface facing the second conductor plane of the dielectric plane, at least one of whose ends is an open end; and at least one suspended transmission line disposed on the dielectric plane,

wherein the first transmission line and the second transmission line are electrically connected to each other, and

wherein the first transmission line and the second transmission line are disposed around the suspended transmission line.

8. A layered structure comprising:

a first conductor plane and a second conductor plane disposed in parallel;

a third conductor plane that is disposed in parallel to the first conductor plane and the second conductor plane, and in parallel to the surface of the second conductor plane opposite to the surface facing the first conductor plane;

a first dielectric plane that is disposed in parallel to the first conductor plane and the second conductor plane between the first conductor plane and the second conductor plane via a hollow region;

a second dielectric plane that is disposed in parallel to the second conductor plane and the third conductor plane between the second conductor plane and the third conductor plane via another hollow region;

a first transmission line that is disposed on a surface of the first dielectric plane facing the first conductor plane, and on a surface of the second dielectric plane facing the surface of the second conductor plane, and at least one end of which is an open end;

a second transmission line that is disposed on a surface of the first dielectric plane facing the second conductor plane and on a surface of the second dielectric plane facing the third conductor plane, and at least one end of which is an open end;

a first suspended transmission line that is disposed on the first dielectric plane, and one end of which is an open end; and

a second suspended transmission line that is disposed on the second dielectric plane, and one of which is an open end;

wherein the second conductor plane includes an opening at a position opposing to an open end of the first suspended transmission line and an open end of the second suspended transmission line;

wherein the first transmission line and the second transmission line are electrically connected to each other; and

a plurality of unit structures are disposed to surround open ends of the first suspended transmission line and the second suspended transmission line, where the unit structure is configured by the first transmission line and the second transmission line.

9. An antenna structure comprising:

a first conductor plane and a second conductor plane disposed in parallel;

a dielectric plane that is disposed in parallel to the first conductor plane and the second conductor plane between the first conductor plane and the second conductor plane via a hollow region;

a first transmission line that is disposed on a surface facing the first conductor plane of the dielectric plane, at least one end of which is an open end; and

a second transmission line that is disposed on a surface of the dielectric plane facing the second conductor plane, at least one end of which is an open end; and

a suspended transmission line that is disposed on the dielectric plane, and one of which is an open end;

wherein the first conductor plane includes an opening at a position opposing to an open end of the suspended transmission line;

the first transmission line and the second transmission line are electrically connected to each other; and

a plurality of unit structures are disposed to surround an open end of the suspended transmission line, wherein the unit structure is configured by the first transmission line and the second transmission line.
